UNITED STATES PATENT OFFICE.

VIRGINIA WINN DARLING, OF YONKERS, NEW YORK.

LAMP SHADE.

1,413,520.

Specification of Letters Patent. Patented Apr. 18, 1922.

Application filed November 27, 1920. Serial No. 426,795.

To all whom it may concern:

Be it known that I, VIRGINIA WINN DARLING, a citizen of the United States, and resident of Yonkers, in the county of West Chester and State of New York, have invented a new and Improved Lamp Shade, of which the following is a full, clear, and exact description.

It is well appreciated that it has been quite customary to provide receptacles for various classes of goods, such as confectionery, and more particularly candy, which receptacles are of a highly ornate nature.

These receptacles have included a body or lid portion, or in other words, that portion which presented the exterior wall of the receptacle, which lid or body portion is of silk, parchment, and various other expensive materials, and quite often designs have been painted by hand thereon.

In connection with this class of receptacle, a factor acting as a detriment to their sale has always been attributed to the fact that the receptacles, although presenting an extremely fine appearance at the time of their initial use, have been of no value subsequent to the completion of its use; and have for the most part been destroyed irrespective of the fact that it involved quite an expenditure of money at the time of their purchase.

It is now an object of my invention to provide the exposed portions, i. e., that portion of the receptacle visible to the casual observer, of such a nature as to permit of its subsequent utilization as an ornamental lamp shade.

Thus it will not be necessary for the purchaser to discard the receptacle which has been purchased at a high figure, and presents an extremely pleasing appearance, subsequent to embodying the same as the main portion of the receptacle, or in other words, the most expensive part of the same may be put to an extremely useful subsequent purpose.

A further object of my invention is that of providing the exposed portion of a receptacle in various shades and designs in the connection aimed, and which receptacle although more particularly intended for use in connection with the receiving of candy and confectionery, is not necessarily limited to this particular adaption.

Reference is had to the attached sheet of drawings as illustrating various practical

embodiments of my invention, and in which—

Figure 1 is a perspective view of a receptacle embodying my invention. 60

Figure 2 is an enlarged sectional view taken along the line 2—2 of Figure 1, and in the direction of the arrows.

Figure 3 is a perspective fragmentary view of the lid portion of the receptacle, 65 illustrated in Figures 1 and 2, and showing the same applied to a light fixture subsequent to its removal from the body portion of the receptacle.

Figure 4 is a view similar to Figure 3 70 but showing a slightly different form of lid, and illustrating a different method of adjustment of the same, to the light fixture if this is desired.

Figure 5 is a perspective sectional view 75 of the body of a receptacle, utilizing my invention, and

Figure 6 illustrates in section, the arrangement of the parts of this latter type of receptacle, prior to its adaption to a light 80 fixture.

In these views it will be seen that the reference numeral 10, reference being had to Figures 1, 2 and 3, indicates the highly ornate lid of a receptacle, which contrary to 85 the conventional construction is preferably built upon a wire frame 11.

This frame conveniently includes, any suitable type of fixture, such as clips 12 permitting of its attachment to a source of illumination 13, and it will be noted, reference being had to Figure 2, that the frame portion of the lid interferes in no way with the association of the lid 10 with the body 14 of the receptacle. 95

The body 14 receives in the usual manner, confectionery, or other desirable contents, and with a view of protecting the attaching fixture 12 from the danger of a certain amount of the confectionery adhering thereto, it will be noted, that the receptacle 14 is conveniently provided with a well portion 15, into which the clips 12 or other attaching means may extend. 100

Thus it will be appreciated that a receptacle in the nature of a lamp shade is provided, in which no wire interferes with the regular duties of the receptacle, and by means of which it is permissible, without extravagance to purchase a highly ornate 110 receptacle, for the reason that that portion of the same involving the greatest expense,

may be put to an extremely useful and highly ornate use.

It is well appreciated among lamp shade manufacturers, and users, that clips, such as 5 those illustrated in Figures 2 and 3, do not always prove practical, particularly where the shade is large, and it will be seen reference being had to Figure 4, which illustrates a slightly different form of highly ornate 10 lid, that the frame may include looped portions 16, affording attachment to a suspending means 17, by means of which the entire lid forming the shade may be suspended from, rather than possibly attached to, the 15 source of illumination. It will also be obvious that, as has previously been brought out in connection with the lid 18, illustrated in Figure 4, that providing the same is of a sufficiently small nature, that the framework 20 thereof, may include clips corresponding to the clips 12 of Figure 3, in lieu of the suspending means, which are preferably only resorted to where the lid is of a relatively large size.

25 A further form of lamp shade may be provided, reference being had to Figures 5 and 6, which latter form of lamp shade is particularly adapted to be formed of a larger size of box, and with a view of 30 affording the straight sides presented in connection with the lids or lamp shades 10 and 18. With this in view, the body portion 19 of the box forms the ornate member, and reference being had to Figure 6, it will be 35 seen that a lid 20 of any desired type is associated therewith, in the usual manner. The frame work 21 in this latter type of shade conveniently includes a looped portion 22 affording attaching means for permitting 40 an association of the shade with a source of illumination 23.

As is customary, this looped portion preferably lies in a plane below that of the upper portion of the frame, and it will be 45 obvious that a certain protecting medium will be necessary to retain the contents of the receptacle in spaced relationship with respect to the loop 22. This protecting means may be of any suitable type such as 50 for instance a disk shaped member having its center portion raised, as at 24, its outer edges being conveniently upturned, as at

25. This expedient obviously permits of the filling of the body portion with any desired contents, which latter are prevented 55 from contacting with the parts of the frame.

Thus, I have provided a receptacle, either of the portions of which may be subsequently utilized to provide a useful and ornamental article, so that the expense incident to the initial purchase of the same is more than justifiable.

It will also be appreciated that obviously numerous modifications of structure and variations of design and material may be 65 resorted to without in the least departing from the spirit of my invention, which I claim as—

1. A device of the class described comprising a receptacle including a lid and body portion, one of said portions being in the nature of a finished lamp shade.

2. A device of the class described, comprising a receptacle, including a lid and body portion, one of said portions being of 75 a highly ornate character and translucent, and being in the nature of a finished lamp shade.

3. A device of the class described, comprising a receptacle including a body and lid portions, a frame attached to one of said portions, the portion to which said frame is attached being translucent and being in the nature of a finished lamp shade.

4. A device of the class described, comprising a receptacle including a lid and body portion, one of said portions being translucent, a framework associated with said translucent portion, and securing means attached to said framework whereby said latter portion is in the nature of a complete lamp shade.

5. A device of the class described comprising a receptacle including a lid and body portion, one of said portions being translucent, a framework attached to said latter portion, securing means attached to said framework permitting of the use of said receptacle portion with which the framework is associated, and means adapted to 100 co-operate with said framework for protecting said members from contact with the contents of said receptacle.

VIRGINIA WINN DARLING.
